UNITED STATES PATENT OFFICE.

EMILE CHARLES, OF PARIS, FRANCE.

ANNOUNCING OR ADVERTISING APPARATUS.

No. 874,832.

Specification of Letters Patent.

Patented Dec. 24, 1907.

Application filed January 27, 1904. Serial No. 190,836.

To all whom it may concern:

Be it known that I, EMILE CHARLES, of 164 Avenue Parmentier, in the city of Paris, Republic of France, gentleman, have invented 5 an Announcing or Advertising Apparatus, of which the following is a full, clear, and exact description.

The invention has for its object an announcement or advertising apparatus for 10 publicity by day and by night, combined in such manner as to cause to appear, in succession, an inscription or subject with different colorings, or to cause to appear, successively, several different inscriptions or sub- 15 jects.

This apparatus is composed in principle of 20 a row of spindles, capable of turning upon their axes, and each carrying a certain number of prismatic bodies the combination of 25 which is arranged so as to form a given inscription, or else, so as to form a foundation on which is painted or otherwise applied a given inscription. Each of the faces of these 30 prismatic bodies is coated with a different color from that of the other faces, or has thereon a part of a letter or the same letter 35 differently colored. It follows that if simultaneous rotary motion is given to all of these spindles, so that one of the faces of a 40 body is substituted for another, the inscription 45 will appear different or differently colored from what it was previous to this partial rotation of the spindles.

In order that the invention may be clearly 50 understood, I have represented an example of the same in the accompanying drawings, in which:

Figures 1 and 1^a are front elevations of 55 the two ends of one form of my invention; 60 Figs. 2 and 2^a are plans of the two ends of the same, part of Fig. 2 being in section on the line A—B of Fig. 1. Fig. 3 is a trans- 65 verse section drawn on the line C—D of Fig. 1. Fig. 4 is a transverse section drawn on 70 the line E—F of Fig. 1^a. Fig. 5 represents a 75 modification of the arrangement represented in Fig. 1. Figs. 6 and 7 are detail views of 80 the prismatic bodies.

In all the figures, like parts are indicated 85 by similar letters of reference.

The apparatus represented at Fig. 1 com- 90 prises, as essential elements, a certain number of spindles *a* arranged perpendicularly 95 between outer cross bars *b* *b'* and intermedi- 100 ate cross bar *b*². These spindles are pro- 55 vided at their upper ends with trunnions *c* entering bearing holes in the bar *b*, and, below, are furnished with a fork *c'* which connects, by a pin, with the shaft of a toothed wheel *d* rotating between the two lower bars 60 *b'* *b*². Each of these wheels *d* is separated from its neighbor by other wheels *d'*, in order that all the wheels *d* may rotate in the same direction.

On the spindles *a* are mounted prismatic 65 bodies *e*. In the accompanying drawings, the bodies are formed of a triangular prism, the three parallel edges of which are vertical, and the three faces of which are painted or otherwise made of three different colors. On 70 each of these spindles are mounted any given number of bodies so as to form in their combination an inscription, such, for instance, as that represented at Fig. 1. It is clear that if 75 each of the spindles, by means of the gearing, is caused to rotate a third of a revolution, for the face first turned towards the public another, differently colored, will be substituted. The new faces will evidently 80 form the same inscription or device as before. The motor which communicates this third of 85 a rotation, every minute for example, may be of any suitable character. That represented in the accompanying drawings, as an example, is composed of a clock movement *g*, Fig. 3, which tends constantly to give rotation to a train of gearing, and of an escapement *h* controlled by another movement not shown in the drawing and which renders 90 the spindles immovable during the desired 95 time. For this purpose, as shown at Fig. 4, *i* is a cam which rotates by the action of the movement *h*, and the profile of which is such as to cause a lever *j*, carrying a stop piece *k*, to oscillate. On the shaft of one of the 100 wheels is mounted a drum *l* furnished with three pins *m*, which, by coming in succession against the stop piece *k*, produce from this face the stoppage of the train of gearing *d* *d'*. When the lever *j*, by the action of the cam, allows a pin *m* to pass, the train *d* *d'* driven by the movement *g* rotates rapidly, but the rotation is limited to a third of a complete revolution by the following pin *m* coming into contact with the stop piece *k*. The motor will be of strength to overcome the resistance of the train of gearing and may be 105 electric, hydraulic, steam, wind, etc.

For day announcements or advertisements they may be constituted of glass formed with facets or furnished with mirrors so as to scintillate in the sunlight. The rotation of the spindles may be intermittent or continuous, slow or rapid at will.

In Fig. 5 the prismatic bodies are arranged with the least possible space between them along the entire length of the spindles. On 10 the foundation thus formed is painted or otherwise executed an inscription or a subject of any desired character. The spindles then rotating to such an angle that other faces are substituted for those previously 15 turned towards the public, the foundation will present another inscription or another subject, or even the same inscriptions or the same subjects on a similar or different foundation. If the prismatic bodies have four 20 faces, for example, the combination will thus furnish four different subjects or inscriptions, or else the same inscriptions or subjects in four different colors.

In the arrangement represented as an example in the accompanying drawings, the intermediate wheels d' have no other object than to produce the rotation of the prisms in the same direction.

Finally this arrangement of announcement or advertising apparatus may comprise additions which would not change the principle of the invention as defined by the appended claims, and it may be modified in details of the driving apparatus and parts 30 which are represented in the drawings only as an example.

Claims.

1. The combination of a plurality of spindles, a series of display devices mounted thereon and arranged to form a letter, the 40 said display devices having a plurality of faces presenting the same form, whereby the letter remains constant when different faces are presented, the said faces being differently colored, and means for rotating said 45 spindles.

2. In a display apparatus, the combination of a plurality of display devices arranged to produce a design the form of which remains constant, each display device having 50 a number of faces of the same constant form, but of different appearances, each face being adapted to be brought into position to form part of the design, and means for moving said display devices simultaneously to 55 present a different set of faces to the front.

3. An advertising device comprising a series of blocks arranged to produce an inscription or design, the several faces of each block presenting a different color, but the inscription or design or the part thereof on the several faces remaining constant in form, and means for simultaneously moving the blocks.

The foregoing specification of my "ar- 65 rangement of announcing or advertising apparatus" signed by me this 31st day of December, 1903.

EMILE CHARLES.
